Primary Examiner — Rashida Johnson(74) Attorney, Agent, or Firm — Laurence A. Greenberg; Werner H. Stemer; Ralph E. Locher(57) CLAIM

The ornamental design for bathing suit with rear openings, as shown and described.

DESCRIPTION

The sole FIGURE is a rear elevational view of a bathing suit with rear openings showing my new design.

The uniformly spaced broken lines on the surface of the bathing suit represent stitching. The remaining broken lines, showing a waistband and portion of the human form, show details which form no part of the claim.
